UNITED STATES PATENT OFFICE.

ALBERT MAURER, OF NEW YORK, N. Y.

TABLE FOR RADIO APPARATUS.

Application filed January 28, 1924. Serial No. 688,905.

To all whom it may concern:

Be it known that I, ALBERT MAURER, a citizen of the United States, and a resident of New York city, in the county of New York and State of New York, have invented 5 certain new and useful Improvements in Tables for Radio Apparatus, of which the following is a specification.

The invention relates to an article of 10 furniture such as a table or cabinet for mounting readily therein an antenna of the loop type as used in radio reception; and it has for its object to so mount the same therein that it will not project beyond the 15 structure during operation and that it may conveniently be rotated to various positions in selecting a station, as by a manually operable member extending beyond the outer edge of the top of the table portion of the 20 cabinet. The invention has for a further object to provide a loop support which will admit of expeditiously securing the said loop to the top of the table in manner to be rotatable relatively thereto. A further object 25 of the invention consists in so constructing the improved article that a smooth table top may be presented for receiving and loud speaker apparatus, and that the loop as well as any other apparatus supported in the structure may be entirely concealed, if desired.

The nature of the invention, however, will best be understood when described in connection with the accompanying drawings, in 35 which—

Fig. 1 is a front view of the improved cabinet with loop in position, and the control shaft therefor shown in section.

Fig. 2 is a vertical section taken on the 40 line 2—2, Fig. 1.

Fig. 3 is an enlarged detail section illustrating the manner of mounting the loop shaft.

Similar characters of reference designate 45 corresponding parts thruout the several views.

Referring to the drawings, 10 designates a table top of suitable dimensions and which is supported upon uprights, preferably in 50 the nature of metal tubes 11, and braced by similar members 12, the cabinet preferably also being divided off into two compartments 13 and 14. When thus divided, the former is provided with shelves 15 as for 55 supporting the (A) and (B) batteries and like apparatus utilized in connection with

radio receiving and loud speaking apparatus 16 which may be supported upon the upper surface of the table 10, it being desirable usually to conceal the former. In the compartment 14, the arrangement is such that a loop antenna 17 may be completely rotated therein, and the same depends for this purpose from the table top 10. To this end, a sleeve 20 is provided thru the table 60 top and extends slightly below the lower surface thereof as shown. Thru this sleeve is designed to pass for rotation therein a screw, the shank 21 of which fits thru said sleeve and whose head 22 is counter-sunk in the 65 upper end of the sleeve and is substantially flush with the upper surface of the table. The threaded end 23 of the screw is screwed into the shaft end 24 or axle of the loop and effects thereby a rigid connection between the two. This arrangement affords a 70 very convenient means for securing the loop to the table, as the same may be expeditiously performed from the upper surface of the table by the use of an ordinary screw driver. 75

The shank 21 carries, also, a worm wheel 25 which it will be understood is to be secured to the shank prior to the attachment of the loop thereto and said worm wheel is designed to mesh with a worm 26 on a 80 worm shaft 27 extending beneath the table to beyond the outer edge of said top so as to be readily accessible for manual operation. Suitable hangers 28 secured to the under face of the table afford bearings for this shaft; 85 and the same carries at its outer end means for effecting rotation of same, for example, a graduated dial member 29 such as is commonly employed in connection with radio apparatus and whereby it will be possible 90 readily to set the loop to a selected or predetermined position. It will be understood, moreover, that this is effected conveniently by turning the knob 30 thereon in the usual manner, which rotates thereby the worm 95 shaft and worm 26 and thru the engagement of the latter with the worm wheel 25 effects a corresponding rotation of the loop.

By the arrangement hereinbefore described, a connection between the shaft or 100 axle 24 of the loop and the means for rotating same is conveniently provided for; and, as aforesaid, the entire apparatus contained within the structure or cabinet may be concealed, for example, by providing suitable 105 curtains 31 which may be drawn thereover. The receiving and loud speaking apparatus

16 will be supported in the usual manner on the top of the table 10; and while the loop itself and other apparatus is wholly concealed as aforesaid, setting of the said loop 5 may nevertheless be conveniently effected as by merely turning the knob 30.

I claim:—

1. In a structure of the character described: a suitably supported table top, a 10 sleeve passing therethru, a screw having its shank passing thru the sleeve and its head substantially flush with the upper surface of the table top and counter-sunk in the said sleeve, a loop antenna having the end of the screw 15 screwed therein to fixedly secure the said loop to the screw, gearing operatively connected with the shank of said screw, and means to rotate said gearing for positioning the loop.

2. In a structure of the character de- 20 scribed: a suitably supported table top, a sleeve passing therethru, a screw having its shank passing thru the sleeve and its head substantially flush with the upper surface of the table top and counter-sunk in the said 25 sleeve, a loop antenna having the end of the screw screwed therein to fixedly secure the said loop to the screw, a worm wheel on the screw shank, a worm shaft and worm rotatably secured to the underside of the table 30 top, the worm meshing with the worm wheel and the worm shaft extending beyond the edge of said table top, and means at the outer end of the worm shaft to rotate same.

Signed at New York city, in the county 35 of New York and State of New York this 24th day of January A. D. 1924.

ALBERT MAURER.
